UNITED STATES PATENT OFFICE.

MAJOR DANE PORTER, OF SOMERVILLE, MASSACHUSETTS.

FIBER CONTAINER.

No. 906,157.

Specification of Letters Patent.

Patented Dec. 8, 1908.

Application filed April 19, 1904. Serial No. 203,855.

To all whom it may concern:

Be it known that I, MAJOR D. PORTER, a citizen of the United States, residing in Somerville, in the State of Massachusetts, have invented certain new and useful Improvements in Fiber Containers, of which the following is a specification, reference being had to the accompanying drawings, forming a part hereof.

10 The object of this invention is to produce a bottle or other similar package for liquids or other substances which shall be practically unbreakable, light in weight, inexpensive and of such construction that the opening thereof for the discharge of the original contents shall effect such change in the structure of the bottle as to make it impossible for the bottle to be used again without immediate detection. Furthermore, the structure of 20 the improved bottle or package is such that when it is made in a form substantially like that of an ordinary bottle it is possible to nest the bottles or to pack one partly within another for purposes of transportation, 25 whereby a great saving in bulk is secured, as well as in weight. The cost of production, moreover, as compared with that of the ordinary glass bottles used for similar purposes, is such that the bottle can be sold at a price 30 which will not be materially greater than the cost of cleansing a glass bottle, particularly when the item of breakage is taken into consideration. As a new clean bottle, manufactured and handled under antiseptic conditions can thus be provided for each filling, all 35 danger of contamination of the contents through imperfect cleansing is avoided. The construction of the bottle also permits it to be not only easily formed but to be formed 40 with such embossed lettering as may be desired for each customer. The filling of the bottle originally can be effected more readily than is possible in the case of an ordinary glass bottle and the opening of the bottle for 45 the discharge of the original contents can be effected easily without requiring the use of a cork screw or of any other special tool.

The material of which the bottle is made is paper or fiber pulp which preferably is so 50 treated as to render it absolutely non-absorbent, impermeable, and incapable of affecting in any manner the flavor or other qualities of the contents.

In accordance with the invention the closure of that portion of the container which in 55 the withdrawal of the contents of the con-

tainer constitutes the discharge orifice is made integral with the body and must be cut or broken or torn off when the contents of the bottle are to be removed, while the filling 60 orifice, independent thereof, preferably at the bottom of the bottle, is closed hermetically, after the bottle has been filled, by a closure which is preferably of the full diameter of the body, this closure being of such a 65 character and so secured to the body as to be practically incapable of removal without destroying the bottle.

The invention will be more fully explained hereinafter with reference to the accompanying 70 drawings exemplifying what I believe to be the best form of the present invention.

In said drawings, Figure 1 is a vertical section of my container, complete and closed. Fig. 2 is a detail view in section of the upper 75 part of the container, showing the cap removed and reversed in the mouth of the container and used as a stopper therefor. Fig. 3 is a detail view of the ring for securing the closure. Fig. 4 is a view showing several 80 containers nested for shipment in an inclosing package.

In form the container may be made to suit the requirements of its intended use, but for holding most liquids the form of the container is preferably substantially like that of an ordinary glass bottle, since that form lends itself readily to the nesting of several bottles 85 for shipment.

As clearly shown in Fig. 1, the body *a*, 90 preferably slightly tapering for convenience in nesting, the neck portion *b*, if the form of the bottle permits it to be so distinguished, and the closure *c* of the upper end or mouth or discharge orifice of the bottle, are all 95 made in one integral piece, having no aperture or opening of any kind, whether filled with a stopper or not, until such time as the contents of the bottle are to be withdrawn, when an opening for the discharge of the contents is made by cutting, breaking or tearing off the cap *c* or by punching a hole through the cap or in some other convenient manner.

As the bottle comes from the factory and is delivered to the customer to be filled, the 105 bottom or the end or portion opposite the cap *c* is open, preferably for the full diameter of the bottle, as represented, for example, in Fig. 4, forming the filling orifice. For the purpose of permanently closing this filling 110 orifice, when the bottle has been filled, there is provided a suitable separate closure *d*

which is adapted to be tightly and permanently secured in the filling orifice in any suitable manner. This closure *d*, which is preferably a compressed or molded disk of 5 wood pulp or other suitable fibrous material, is here shown as held in place by a washer or ring *i*, the edges of which are sprung into place in a recess *e* and seated upon a shoulder *f* with which the body *a* of the container is 10 formed. This spring ring *d* may be cemented, if necessary, to the body of the container.

If it be desired to close temporarily the discharge orifice of the bottle, after it has 15 been opened, the cap *c*, may be of suitable form and size to enter the mouth of the bottle, when cut off and reversed, as shown in Fig. 2, to form a stopper therefor. In this case it is desirable to weaken the neck wall 20 in a circumferential line, as at *l*, and to thicken the wall above and below such weakened line, as at *m* and *n*, to strengthen the wall and to form flanges for coöperation when the cap is removed and reversed. For 25 the shipment of the empty bottles they may be conveniently nested and packed in a suitable case *p*, as represented in Fig. 4, the closures *d* being packed separately.

The bottles may be formed of paper or 30 wood pulp or other suitable fiber, having mixed therewith a suitable binder, if desired, and they are preferably made in suitable molds in which the pulp or fiber is compressed to secure the desired density or hardness. It will be observed that the shape of 35 the bottle shown in Fig. 2 is well adapted for this process of manufacture. Such waterproofing substances as may be desired may be added to the pulp before formation of the 40 bottle or may be applied to the bottle after formation as may be desired. It will be ob-

vious, however, that the present invention is not particularly concerned with the process of manufacture of the container and that changes in the herein-described details 45 may be made without departing from the spirit of the invention or the scope of the subjoined claims.

I claim as my invention.

1. A fiber container having the portion 50 thereof which in use constitutes the discharge orifice covered by a cap which is formed integral with the body of the container and forms one end of the latter, said body having a line of weakness at its cap portion and flanged above the latter to provide the cap with a shoulder, the portion of the cap above said flange being of external diameter approximately the same as the internal diameter of the contiguous portion of 55 the body of the container; the other end of said container constituting a filling opening, and a closure for the filling opening permanently secured to the body of the container.

2. A fiber container having the portion 60 thereof which in use constitutes the discharge orifice covered by a closure which is formed integral with the body of the container and forms one end of the latter; the other end of the container constituting a filling opening 65 and provided with a shoulder contiguous thereto, and a closure for said filling opening permanently secured thereto and comprising a disk and a spring ring, the latter adapted to be sprung into place and to secure the 70 disk.

This specification signed and witnessed this sixteenth day of April, A. D., 1904.

MAJOR DANE PORTER.
